UNITED STATES PATENT OFFICE.

RAYMOND R. PULLEN, OF OCEANIC, NEW JERSEY.

DISPLAY DEVICE FOR FLAGS.

1,268,488.

Specification of Letters Patent.

Patented June 4, 1918.

Application filed July 10, 1917. Serial No. 179,707.

To all whom it may concern:

Be it known that I, RAYMOND R. PULLEN, a citizen of the United States, residing at Oceanic, Monmouth county, State of New Jersey, have invented new and useful Improvements in Display Devices for Flags, of which the following is a specification.

The display device of this invention is particularly adapted to hold and display flags. It is a light metal structure provided with a clamp for fastening it to any suitable support or the front part of an automobile, as for instance the filling cup of the radiator. It also includes means for holding a vertical rotatable shaft carrying an attractive object or objects, preferably flags. To insure auto-rotary action of the flags and shaft the flags extend in opposite directions from the shaft. The flags are made of a stiff or rigid material, which may be sheet metal, and are so curved or bent as to offer resistance to air currents at one side of the shaft and to spill the air at the other side of the shaft. The device also comprises laterally extending branches or arms, the ends of which are provided with means for holding the staffs of other flags, preferably in inclined positions. These flag holding means consists of bends at the ends of the lateral arms having a certain amount of resiliency and suitably perforated to act as clamps for the staffs of the flags, placed through the perforations. The perforations or holes are so located that when the bends are compressed the holes will aline for the free admission of the staffs, and the holes will firmly grip the staffs by the resiliency of the bends when the same are released, and so securely hold the flags in set positions.

All parts of the display device may be integral, suitably shaped by a punching process, the various parts being formed or bent into shape to properly perform the desired functions. Or the parts may be made separately and then connected together to constitute a complete display device.

The accompanying drawings illustrate an embodiment of the invention.

Figure 1, is a face view of the device complete.

Fig. 2, a plan view of the same.

Fig. 3, a vertical central section; and

Fig. 4, shows a blank, in the flat, adapted to be formed into shape, as shown in the other views.

Fig. 4 shows a properly shaped blank

from which the device may be made. It comprises two lateral extensions 5, 5, each having a puncture or hole 6, 6, at its end; two lateral bars 7, 7, adjacent the extensions 60 5, 5, and each having two holes 8, 8, at its end, an extension 9, at right angles to 5 and 7, and punctured by a hole 10, at its end. The extension 9, has also a hole 11, mediate 65 its ends and a tongue 12, slit from its end adjacent the bars 7, 7. It may be expedient from a manufacturer's view-point to build the device up from separate pieces; in such case the parts 5, 5, and 9, may be secured together by rivets, as indicated by dotted circles 13, 13, and the bars 7, secured to the part 9, as indicated by the dotted circles 14, 14. In other views the parts 7, and 9, connecting rivets 14, 14, are shown in full, the parts 5, 5, and 9, being integral. 70

The clamp feature of the device is made from the parts 5, 5, bent so as to embrace any suitable support and securely held thereon by a screw bolt 15, passed through the holes 8, 8, so as to draw the ends of the 75 clamp together. It is shown in Figs. 1 and 3 embracing the filling cup 16, of the radiator of an automobile. The means for holding a rotatable object is composed of the part 9, which is bent on the lines 17, to 80 bring the holes 10 and 11, in alinement. The tongue piece 12, is bent downwardly and forwardly to bring its end beneath the hole 11, to act as step bearing 18, for the end of the shaft 19, which is free to rotate in 85 the bearings 10 and 11. This shaft 19, may carry any auto-rotary objects; represented as double flag 20, which is printed, or otherwise impressed or marked on both sides of a sheet of a suitable rigid material that will 90 maintain curvatures formed at its edges, such as shown in the plan view Fig. 2. The convex sides of the object 20, offer less resistance than the concave sides to currents of air when the device is stationary and 95 when it is carried on a moving vehicle. A single flag may be applied to each side of the object. 100

The bends formed at the ends of the branches or bars 7, 7, as shown in Fig. 1, 105 are resilient and the holes 8, 8, are located in the bends in such manner that when the bends are somewhat closed by pressure applied to their ends 21, the holes will aline to afford a free passage for the insertion of 110 a stick or rod of a display object therein. The resiliency of the bends will, when their

ends are released, cause the stick or rod to be securely gripped by the edges of the holes. Small flags 22, 23, are shown as the objects carried at the ends of the bars 7, 7, 5 their staffs 24, being of a size to be adequately held in the holes 8, 8, of the resilient bends.

I claim:

1. A display device, comprising a clamp 10 for securing the device to a support in operative position, an extension having holes adapted to act as bearings for the vertical shaft of a rotatable object and a tongue cut from the base of the extension and formed 15 to act as a step bearing for the vertical shaft and lateral branches or bars each provided at its end with means for holding the staff of a flag.

2. A display device, comprising a clamp 20 for securing the device to a support in operative position, means centrally located on the device for holding a rotatable object having a vertical shaft and lateral branches or bars each having at its end a resilient 25 bend provided with holes adapted to grip and firmly hold the staff of a flag by the resiliency of the bend.

3. A display device, comprising a clamp for securing the device to a support in operative position, an extension having holes 30 adapted to act as bearings for the vertical shaft of a rotatable object and a tongue cut from the base of the extension and formed to act as a step bearing for the vertical shaft, and lateral branches or bars each having at 35 its end a resilient bend provided with holes adapted to grip and firmly hold the staff of a flag by the resiliency of the bend.

4. A display device, composed of sheet metal having side pieces adapted to be 40 formed into a clamp for securing the device to a support, a central extension having holes formed therein and a tongue piece cut therefrom and bent to bring the holes and the end of the tongue in alinement, and lateral branches having their ends bent with 45 two holes in each bend angularly arranged.

Signed at New York, county and State of New York, this 9th day of July, 1917.

RAYMOND R. PULLEN.
